SEALED WET END FOR PAPER MACHINES

John E. Goodwillie, Beloit, Wis., assignor to Beloit Iron Works, Beloit, Wis., a corporation of Wisconsin

Application February 13, 1946, Serial No. 647,367

6 Claims. (Cl. 92—43)

1

This invention relates to a wet end for a paper making machine which effects pressure formation of paper stock into a paper web free from streaks, uneven weight distribution, and uneven fiber arrangements.

Specifically, the invention deals with a paper machine wet end which forces paper formation from a stock pool before the stock issues from under a slice and up to the point where the web is removed from its forming surface by subjecting the stock and web on the forming surface to materially higher absolute pressures than those existing under the forming surface.

In paper making machines equipped with conventional wet ends and head boxes, currents or swirls of paper stock are produced in the head boxes, and these currents have cross-flow velocity components which are effective to move part of the stock on the forming surface of the machine from its original position and pile it up in another position where the drainage of water through the forming surface sets the stock into streaked shetts. Streaked sheet formation is more prevalent on conventional high-speed paper machines because, on such machines, the sheet must set quickly, and the streaks are not evened out.

The present invention now provides a high-speed wet end for paper machines that eliminates streak formation by effecting the formation in a confined chamber in the presence of an excess of amount of stock and water. Any cross movement at a point where stock is forming on the wire does not, in the machines of this invention, result in the formation of streaks because the pool of stock and water continues to feed the forming area at all points. In the machines of this invention the stock, while it is still in a fluid pond state, is caused to move with the forming surface in the same direction as the forming surface to eliminate disposition of fibers parallel with the direction of movement of the forming surface. Pressure formation occurs in advance of the slice and continues beyond the slice up to the point where the web is removed from the forming surface.

In the preferred embodiment of the invention, a foraminous cylinder, such as a cylinder mold, receives an endless forming wire therearound. This forming wire is also trained around guide rolls spaced from the cylinder to direct the wire onto and off of a portion of the periphery of the cylinder. A stock chest, or feed box, is provided adjacent the ascending side of the cylinder and has a seal projecting therefrom into sealing relation with the forming wire on the cylinder. The stock chest carries a slice in spaced relation from the seal, and stock in the chest communicates directly with the forming wire along a formation zone between the seal and slice. The stock is maintained under pressure and may be circulated

2

through the formation zone at any desired speed. A suction couch roll cooperates with the forming wire adjacent its point of removal from the cylinder. This point is preferably adjacent the descending side of the cylinder so that the stock on the wire will travel around the top portion of the cylinder between the slice and the couch roll. A sealing roll is provided in pressure nip engagement with the couch roll and cooperates with end walls and seals to provide a sealed chamber above the cylinder beyond the slice. A felt guide roll is adjustably mounted in this chamber and receives a pick-up felt therearound to direct this felt through the nip between the couch roll and forming wire for picking up the newly-formed web from the forming wire. The sealed chamber is pressurized with compressed gas such as air to force drainage through the forming wire and cylinder. The drained white water in the cylinder can drop freely through the lower portion of the cylinder into a drainage sump which, if desired, can be evacuated.

The pressure formation occurring on both sides of the slice in the machine of this invention eliminates streaks or uneven fiber formation and, at the same time, makes possible extremely high speed paper formation.

It is, then, an object of this invention to provide a paper making machine with a pressurized wet end that eliminates uneven fiber formation and can be operated at very high speed.

A further object of this invention is to provide a compact wet end for paper making machines that forces drainage of white water through a forming surface continuously from the time stock is initially deposited onto the forming surface until the paper web is removed from the forming surface.

Another object of this invention is to provide a wet end for paper making machines wherein stock under any desired pressure flows at any desired speed against a moving forming surface, and is ejected under a slice directly into a pressurized chamber for forcing drainage of white water from the web being formed on the surface until the web is removed from the surface.

A still further object of this invention is to provide a sealed wet end for paper making machines having a pressurized formation chamber receiving the forming run of a forming wire therethrough together with a pick-up felt for removing the web from the forming wire before releasing pressure on the web.

A still further object of this invention is to provide a shiftable couch roll arrangement for a sealed paper machine wet end which accommodates movement of the couch roll without breakage of the suction connection.

A still further object of this invention is to

provide a suction roll assembly wherein drainage is effected through bellows type conduits that accommodate movement of the roll without breakage of drainage connections.

Other and further objects of the invention will be apparent to those skilled in the art from the following detailed description of the annexed sheets of drawings which, by way of a preferred example only, illustrate one embodiment of the invention.

On the drawings:

Figure 1 is a side elevational view of a sealed wet end for a paper making machine in accordance with this invention.

Figure 2 is a longitudinal cross-sectional view, with parts in elevation and with parts diagrammatically illustrated, of the wet end of Figure 1.

Figure 3 is a fragmentary transverse cross-sectional view, with parts in elevation, taken along the line III—III of Figure 1.

Figure 4 is a fragmentary transverse cross-sectional view, taken along the line IV—IV of Figure 1.

Figure 5 is a fragmentary transverse cross-sectional view taken along the line V—V of Figure 1.

As shown on the drawings:

The sealed wet end 10 of this invention, as shown in Figure 1, includes transverse supporting beams 11 and 12 carrying removable upright pedestals or columns 13 and 14 which columns, in turn, respectively support box frames 15 and 16. It should be understood, of course, that similar uprights or columns 13 and 14 are provided on the rear end of the machine for supporting the other end of the box beams 15 and 16. Brackets 17 are provided on the beam 15 for supporting bearings 18 which rotatably carry a guide roll 19 between the columns 13.

Longitudinal beams 20 supported from the beams 15 and 16 carry bearings 21 for a foraminous cylinder 22. The cylinder 22 has axes 23 rotatably mounted in the bearings 21.

A pan or tank 24 surrounds the lower portion of the cylinder 22 and is carried by the beams 15 and 16 as better shown in Figure 2. This tank provides a drainage vat for the cylinder as will be more fully hereinafter described, and has an outlet sump 24a in the bottom thereof for removal of white water.

The beam 16 carries brackets such as 25 which support bearings such as 26 for a guide roll 27. A cross shaft 28 is journaled in the brackets 25 and has links 29 secured on the ends thereof. The lower ends of the links 29 are pivoted to the rear ends of brackets 30 which carry bearing supports 31 for another guide roll 32. Additional links 33 pivotally connect the forward ends of the brackets 30 with the forward ends of the brackets 25. A gear segment 34 is secured on the shaft 28 and meshes with a gear 35 on a shaft 36 carried by pedestals such as 37. Rotation of the shaft 36 will rotate the gear 35 to swing the gear segment 34 for rotating the shaft 28 and thereby swinging the links 29 to shift the brackets 30 for swinging the guide roll 32 relative to the guide rolls 19 and 27. A forming wire 38 is trained around all of the guide rolls, and also around the top portion of the cylinder mold 22 and the shiftable guide roll 32 maintains the forming wire 38 in a tightened condition. A cam 39 secured on the shaft 36 has a cable 40 trained therearound and secured thereon. Counterweights 41 are suspended on this cable for tending to rotate the shaft 36 in a clockwise

direction thereby tending to drive the gear 35 for raising the gear segment 34 and lifting the links 29. Raising of the links 29 moves the bracket 30 and roll 32 in a direction to tension wire 38 and by properly proportioning cam 39 and counterweights 41, the weight of the moving parts can be counterbalanced, regardless of their position. A second cam 42 is also secured on shaft 36 and receives a cable 43 therearound which is anchored thereto. Tension weights 44 are suspended on cable 43 and also tend to rock the shaft 36 in a clockwise direction to raise brackets 30. By properly proportioning cam 42 and tension weights 44 it is possible to apply a predetermined tension on the forming wire regardless of position of roll 32. The arrangement is such, therefore, that the roll 32 is shifted in response to changes in length of the forming wire 38 for maintaining a predetermined tension on this wire.

The above described structure is straddled by another frame construction comprising uprights 45 supporting longitudinal box beams 46 in spaced relation above the cylinder 22. A stock chest or feed box 47 is mounted within the frame structure adjacent the cylinder 22. This stock chest 47 includes, as best shown in Figure 2, a vertical passageway P as wide as the forming wire 38 and receiving paper stock into its lower end from a stock feed pipe 48 fed from a centrifugal stock pump 49 and controlled by a valve 50 in the pipe line 48.

The stock chest 47 has a forwardly projecting lip 47a carrying, at its forward end, a flexible apron seal 51 which rides on the forming wire 38 at a point just after the forming wire engages the ascending side of the cylinder 22. The cylinder 22 is driven in a clockwise direction by a driver connected to one of its axles 23.

The stock chest 47 also has a sloping slice wall portion 47b in spaced relation above the lip 47a thereof and slidably supporting a slice bar 52 adapted to be raised and lowered by screw rods 53 having operating handles 53a. The slice bar 52 carries a tipped end member 54 which projects forwardly therefrom and is adapted to be raised and lowered on the slice bar 52 by rods such as 55 which are actuated by handles such as 55a. Clips such as 56 actuated on by springs 57 hold the tip member 54 in sealed sliding relation on the slice bar 52. The slice member 54 is thus selectively adjustable along its length on the slice bar 52 and the slice bar 52 is adapted to be raised and lowered along the slice wall 47b. The slice member 54 is positioned adjacent the top of the cylinder mold 22 but still on the ascending side of the cylinder and is spaced from the seal 51 to define a formation zone Z on the forming wire and cylinder 60 communicating freely with the interior of the stock chest along the entire width of the forming wire.

A baffle 58 is mounted in the stock chest 47 on a bracket 59 for swinging movement of its free forward end toward and away from the cylinder 22. A clamp 60 cooperates with the bracket 59 to hold the baffle in adjusted position. The clamp mechanism can, of course, be replaced with an operating rod mechanism accessible from outside of the stock chest. The forward free edge 58a of the baffle 58 lies behind the slice wall 47b in spaced relation therefrom so that the formation zone Z communicates between the front edge of the baffle and the slice with a stock surge chamber C in the stock chest above the

baffle 58. Stock from this surge chamber C can drain through a conduit 61 in the back wall of the stock chest immediately above the hinged end of the baffle 58. A pipe line 62 communicates with the drain conduit 61 and a pump 63 in the pipe line 62 can recirculate stock from the chamber C to the inlet pipe 64 for the centrifugal pump 49. A valve 65 controls flow from the pump 63.

The surge chamber C extends upwardly from the baffle 58 for a considerable distance so that, if desired, a high head of stock can be maintained. The top of the surge chamber C is closed by a door 66 so that the entire stock chest can be maintained under pressure. A shower pipe 67 is provided in the upper end of the surge chamber C to destroy foam on top of stock in the chamber and to keep the interior surfaces of the chamber clean. An air space is preferably maintained above the stock and the shower pipe 67 is mounted in this air space.

As best shown in Figure 2, a hollow box beam 68 is carried by the longitudinal top beams 46 and extends transversely therebetween. A top wall member 69 depends from the beam 68. A rear wall 70 depends from the rear of the top wall 69 and has a rearwardly extending portion 70a connected to the front wall of the stock chest 47. A front wall 71 depends from the front end of the top wall 69. Side walls 72 close the ends of the space embraced by the walls 69, 70, and 71 to provide an enclosed space S above the cylinder mold.

Casings such as 73 (Figure 1) are built up on the side walls 72 immediately above the cylinder 22, and have removable end caps 74 secured to their lower ends and to the side walls. As shown in Figure 2, vertical tracks or ways 75 are provided in the casings 73 to slidably support carriages 76 carrying bearings 77 for a felt-directing guide roll 78 which extends transversely across the space S above the cylinder 22. The caps 74 are removable to give access to the bearings 77. Vertical screw rods 79 project upwardly from the carriages 76 and are threaded through worm gears (not shown) in casings 80 mounted on the top beams 46. Worms (not shown) on a transverse shaft 81 mesh with the worm gears in the casings 80 to rotate the gears for raising and lowering the screw rods 79 to thereby adjustably position the felt-directing roll 78. A hand wheel 82 is provided for actuating the shaft 81.

As shown in Figure 1, brackets such as 83 depend from the top beams 46 and carry bearings 84 at their lower ends for rotatably supporting a sealing roll 85 forwardly of the roll 78 and above the cylinder 22. As shown in Figure 2, the front wall 71 carries a seal 86 engaging the periphery of the sealing roll 85. An air tube 87 backs up the seal 86 to urge it into sealing relation with the roll 85.

As best shown in Figures 1 and 3, levers 88 are pivoted to both side faces of both beams 46 to provide four depending couch roll-carrying supports. Each lever 88 has its free depending end pivoted to a link 89. Each pair of links 89, in turn, is pivotally supported from a double diaphragm unit 90 which is more fully described and illustrated in the copending application of Lloyd Hornbostel, Serial No. 607,728, filed July 30, 1945, entitled: "Fluid Pressure Controlled Roll Assembly." These double-acting diaphragm units 90 have a central housing member 90a to which the links are pivoted, and diaphragms 90b over-

lie the top and bottom of the housing. Members 90c are clamped to the central portions of the diaphragms 90b. A rigid carriage 91 clamps these members to transmit forces applied to the carriage through the diaphragm to the housing 90a. Air or other gas is admitted under pressure to the diaphragm chambers in the housings 90a so that the diaphragms are gas-cushioned and will uniformly transmit forces applied to the carriage even when the housings become cocked relative to the carriage. These units 90, of course, could be replaced with simple carriage constructions directly receiving the links 89.

The carriages 91 are slideable on ways provided by brackets 92 mounted on the top beams 46. The brackets 92 each carry a worm and gear casing 93 on the top thereof. A worm gear in each casing 93 receives, in threaded relation therethrough, a screw rod 94 secured to the carriage 91. A cross shaft 95 operated by a hand wheel 96 drives the worms (not shown) in the casings 93 to rotate the worm gears for raising and lowering the screw rods 94 and carriages 91. The levers 88 are thus swung about their pivots on the top beams 46.

Trunnions 97, at least one of which is hollow, are pivotally mounted between each pair of levers 88 on pivots 98. These trunnions 97 have arms 99 projecting forwardly therefrom and equipped with forked or yoked ends 99a. A single-acting diaphragm unit 100, more fully described and illustrated in the aforesaid Hornbostel application Serial No. 607,728, is pivotally mounted in the yoked end 99a of each arm 99. Each unit 100 includes a casing 100a providing a gas chamber and covered with a diaphragm 100b to the central portion of which is clamped a force-transmitting member 100c. This member 100c is coupled through a coupling 101 with a screw rod 102 threaded through a coupling 103 that is pivoted to the ends of each pair of links 88. The screw rod 102 can be adjusted to swing the arms 99 relative to the links 88 and thereby move the trunnions 97 about their pivots 98.

The trunnions 97 carry elbow members 104 with at least one of the members being hollow and communicating with the hollow trunnion 97. These elbow members 104, in turn, support the suction box or gland 105 of a suction couch roll 106. The couch roll 106 includes a rubber-covered perforated cylinder 107 rotatable around the suction box 105 and this cylinder 107 is maintained in nip relation with the sealing roll 85 as best shown in Figure 2.

The hollow trunnion 97 is connected with a deformable bellows conduit 108 extending between the levers 88 to the passageway 109 provided in one of the box beams 46. The passageway 109 is evacuated by a suction pump (not shown) to evacuate the suction box 105 of the couch roll 106. The bellows conduit 108 will permit shifting of the couch roll without breaking the suction connection.

As best shown in Figures 1 and 2, the cross beam 16 supports a hollow box beam 110 on the top thereof and a deformable bellows conduit 111 communicating with the interior of the beam 110 extends upwardly therefrom and is attached to a boss 104a on the hollow elbow member 104 for draining liquids from the interior of the suction box 105 so that these liquids need not be drawn upwardly through the passageway 109. The hollow box beam 110 is evacuated by a suction pump (not shown) and white

water is drained through the bellows conduit 111 into the passageway 110.

As shown in Figure 2, the suction box 105 carries seals 105a acting on the cylinder 101 to define a suction area A on the lower portion of the cylinder. Another seal 105b is carried by the suction box 105 to act on the cylinder 101 adjacent the nip between the rolls 85 and 106. This seal 105b prevents leakage through the perforations in the cylinder 101 from the space S.

A compressor 112, diagrammatically shown as mounted on a beam 48, supplies compressed air through a conduit 113 to the interior of the transverse box beam 68. The compressed air from the box beam 68 is supplied to the space S through ports 114 in the beam 68 and 115 in the top wall 69.

As shown in Figure 1, the side wall 72 for the space S has a seal plate 116 bolted thereon for carrying seals in sealing engagement with the ends of the cylinder 22, the suction couch roll 106, and the sealing roll 85. As shown in Figure 4, the side wall 72 has an outturned ledge 72a with an upstanding flange 72b thereon to which the seal plate 116 is bolted. The cylinder 22 extends into the pocket provided by the ledge 72a and this ledge carries a rubber sealing belt 117 having a grooved face lying in close proximity to the apron cloth seal 51 which rests on the forming wire 38 on the cylinder mold 22. This apron cloth 51 as shown extends between the flange 72b and the seal piece 116 to be clamped therebetween. The seal belt 117 has grooves 118 in the face thereof confronting the apron cloth 51 and water is supplied to the grooves through an inlet passage 119 for preventing lodgment of stock in close clearance spaces particularly in that section beyond the end of apron cloth 51 and where belt 117 is in close clearance relation with the forming wire 38 providing a water seal for the edges of the apron seal 51.

The cylinder 22 has an end ring 22a carrying a smooth faced sealing plate 120 acted on by a sealing block 121 which is slidably carried in the seal casing 116. A rubber tube 122 backs up the sealing block 121 and is inflated to urge the block into sealing engagement with the plate 120 for providing an efficient seal which can be lubricated with water from the grooves 118. The block 121 extends around the lower edge of the side wall 72 and, of course, the identical structure is duplicated at the other end of the mold.

As shown in Figure 5, the air cushioned block 121 extends around the ring 22a of the cylinder mold down to the front lower edge of the seal plate 116 at the point where the suction couch roll 106 is in nip pressure relation with the cylinder 22. The rubber cover 107a on the cylinder of the couch roll 106 terminates inwardly from the ends of the cylinder and the cylinder has a solid metal end portion 107b which is spaced from the cylinder mold 22 and the space between this end portion and the cylinder mold is sealed. Grooves similar to those shown at 118 in the belt 117 can be provided to lubricate the contacting surfaces between block 121 and plate 120. A second arcuate block 123 is backed by another air tube 124 and urged against the edge of the cylinder 107 to seal the end of the suction couch roll. This block 123 extends up to the nip between the rolls 106 and 85 and a third block 125 then extends around the end of the roll 85 as shown in Figure 1.

A tube 126 is secured to beam 110 and contacts the extended portion of the seal plate 116 in the space between the ends of roll 106 and cylinder mold 22 as shown in Fig. 1 to form a positioning support for the extended end of the seal plate 116. The tube can be pivoted on ears 127 on the seal plate. This tube can be supplied with compressed air and communicates with the interiors of the air tubes 122 and 124 to inflate these tubes.

As shown in Figures 1 and 2, a pick-up felt 128 is trained around the suction couch roll 106 and around the felt directing roll 78. The pick-up felt enters the sealed space S through the nip between the sealing roll 85 and the couch roll 106 and then passes around the directing roll 78 to return over the top of the cylinder mold 22 through the nip between the mold and the couch roll 106. As indicated in dotted lines in Figure 2, the directing roll 78 can be raised and lowered so that the felt will have the desired lapping engagement with the web on top of the cylinder 22 and forming wire 38. When the roll 78 is raised to its dotted-line position, the felt engages the web just before it enters the nip between the cylinder and couch roll 106 but, when the roll is dropped to its solid-line position, the felt will lap the web for a considerable distance in advance of the nip.

In operation of the wet end of this invention the cylinder 22 is driven to drive the forming wire 38 trained therearound. Stock is pumped through the passageway P of the stock chest 47 to supply stock under pressure to the formation zone Z. The stock is circulated from the formation zone into the surge chamber C and recirculated from this surge chamber through the pipe line 62 back to the passageway P. The stock can be caused to move in the formation zone at the same speed as the forming wire 38 on which the stock is formed into a web, or at any desired speed relative to the forming wire. The stock is preferably maintained under superatmospheric pressure so that formation in the zone Z will be speeded up. White water drains through the forming wire 38 and cylinder 22 into the interior of the cylinder and then drops through the bottom portion of the cylinder into the vat 24 from which it is removed through the sump 24a. Stock on the wire emerging from under the slice 54 enters the sealed chamber S which is maintained under superatmospheric pressure by air from the compressor 112. Further drainage of white water through the forming wire 38 and cylinder mold 22 thereupon takes place and the stock is immediately set into a web. The web is then covered by the pick-up felt and passes through the nip between the suction roll and cylinder mold while it is sandwiched between the forming wire and the felt. The suction area of the couch roll 106 transfers the web to the pick-up felt and off of the forming wire. The forming wire emerging from the nip is separated from the web and the web travels on the underface of the pick-up felt to the press section and drier section (not shown) of the paper machine. A pan 126 mounted adjacent the couch roll 107 catches water ejected from the holes in the couch roll cylinder to prevent this water from dripping on the web-carrying pick-up felt 128. A seal 105c on the couch roll suction box 105 cooperates with the off-going seal 105a to define a sealed space B in the roll cylinder 107 which will hold water in the holes of the cylinder until these holes are above the bottom of the pan 126 whereupon they will discharge into the pan.

Formation of the web in the zone Z occurs in the presence of an excess supply of stock and water so that cross-current velocities do not cause streaks in the forming sheet. The pressure chamber immediately following the slice insures prompt setting of the stock into a web before any rearrangement of fibers can occur, so that the web will have a fiber structure consistent with the hodge-podge fiber arrangement in the stock pond.

The term "pressurizing" as used herein and in the claims is intended to mean any pressure loading or force.

From the above descriptions it will be understood that this invention provides a sealed pressurized wet end for paper machines wherein web formation both behind and in advance of the slice occurs under controlled pressure conditions which eliminate streaking and directional fiber formation. The machines can be operated at extremely high speeds, are quite compact, and free from heretofore-required shake equipment. Only relatively short forming wires need be used, thereby reducing the cost of wire maintenance.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A sealed wet end for paper making machines comprising a foraminous cylinder, a forming wire trained therearound, guide rolls for directing the forming wire around the upper portion of the cylinder only, a stock chest on one side of the cylinder communicating with the forming wire on the ascending side of the cylinder, a couch roll coacting with the forming wire on the descending side of the cylinder, a sealing roll in nip engagement with the couch roll, wall means carrying seals enclosing a space above the cylinder, and means for introducing gas under pressure into said space for pressurizing said space.

2. In a paper making machine a frame, levers pivoted on said frame, means carried by said frame for swinging said levers, arms pivoted on said levers, means for shifting said arms relative to said levers, bearing brackets on said arms, a suction roll carried by said bearing brackets, a hollow trunnion carried by one of said bearing brackets, a suction box in said suction roll communicating with said hollow trunnion, and a flexible suction conduit for evacuating said trunnion and suction box, said flexible conduit accommodating shifting of the suction roll by said levers and arms.

3. In a paper making machine a rotatable cylinder having a forming surface thereon, structure cooperating with said cylinder defining a sealed space above said forming surface, means for pressurizing said sealed space, a couch roll cooperating with the forming surface for removing a web formed thereon, a guide roll in said sealed space, a felt trained around said guide roll, and means for moving said guide roll in said sealed space toward and away from said cylinder for lapping the felt around a predetermined amount of said forming surface in advance of the couch roll to travel with the forming surface through a nip between the forming surface and couch roll.

4. A sealed wet end for paper making machines comprising a cylinder, a forming wire trained around said cylinder, guide rolls spaced from said cylinder for directing the forming wire around the top portion of the cylinder, a couch roll co-operating with the forming wire on said cylinder, means for moving said couch roll circumferentially of the cylinder to adjust the position of a nip between the couch roll and the cylinder, a sealing roll in pressure nip rotating engagement with the couch roll, seals coacting with the cylinder, the couch roll, and the sealing roll for defining a sealed space above the cylinder, a felt directing roll in said sealed space, and a pick-up felt trained around said felt directing roll having one run passing through the nip between the sealing roll and the couch roll and the other run passing through the nip between the cylinder and couch roll for lapping a web on the forming wire.
5. In a sealed wet end for paper making machines having structure defining a sealed pressurized space above a forming zone on the forming surface of the machine, the improvements of a felt directing roll in said space, a pick-up felt trained around said roll, and means for shifting said roll relative to the forming surface of the machine to adjustably lap the pick-up felt for a predetermined distance on the forming surface.
6. A sealed wet end for paper making machines comprising a foraminous cylinder, a forming wire trained therearound, a stock chest extending along one side of said cylinder and communicating with the wire on said cylinder for depositing stock thereon, a couch roll coacting with said cylinder beyond said stock chest for removing a web from the wire, a felt-directing roll above the cylinder and between the couch roll and stock chest, a felt trained around said directing roll and through the nip between the couch roll and cylinder, means for adjustably moving said felt-directing roll to adjustably lap the felt on the forming wire on the cylinder, seals coacting with the couch roll and the stock chest to define a sealed space above the forming wire on the cylinder and around the felt-directing roll, and means for introducing gas under pressure into said space for pressurizing stock on the forming wire to force drainage therefrom through the wire and cylinder.

JOHN E. GOODWILLIE.
